UNITED STATES PATENT OFFICE

JOSEPH D. MYERS, OF SAVANNAH, GEORGIA, ASSIGNOR TO G. A. BISLER, INCORPORATED,
OF PHILADELPHIA, PENNSYLVANIA, A CORPORATION OF PENNSYLVANIA

BOX

Application filed December 18, 1930. Serial No. 503,140.

This invention, in general, relates to boxes, and more particularly to pasteboard boxes, having for its principal object the provision of a pasteboard box particularly designed and adapted for displaying and dispensing 5 cigars.

Another object of the present invention is to provide an improved pasteboard box as a substitute for the conventional wooden cigar 10 box.

A further object is the provision of a highly efficient, simplified hinge construction particularly adapted for pasteboard boxes.

Other objects and advantages residing in 15 the construction, arrangement, and adaptation of parts will appear more fully in the details hereinafter set forth.

Up to the present time most of the cigars manufactured are packed in wooden boxes 20 which are generally provided with a hinged lid, fabric or paper hinges being frequently employed. These conventional cigar boxes after opening are usually placed in glass cases for display, special means being used 25 for supporting the hinged lids in a vertical or partly inclined position with a view to calling attention to the attractive label pasted on the lid advertising the particular brand of cigars within the box.

By my present invention the hinged lid 30 may be conveniently supported by means of the utmost simplicity and efficiency, forming a part of the box as a whole.

The invention will be best understood by 35 reference to the accompanying drawings, forming part of this application, in which:

Fig. 1 is a perspective view of a cigar box embodying my invention;

Fig. 2 is an end elevational view of the 40 box shown in Fig. 1;

Fig. 3 is a fragmentary longitudinal sectional view, taken on line 3—3 of Fig. 2;

Fig. 4 is a slightly modified form of the 45 invention shown in Figs. 1, 2, and 3;

Fig. 5 is a fragmentary, enlarged, end elevational view of the box shown in Figs. 4, with the lid in closed position;

Fig. 6 is an end elevational view of an 50 other modification of the invention;

Fig. 7 is a fragmentary, transverse sectional view taken on line 7—7 of Fig. 6;

Fig. 8 is an end elevational view with parts broken away, of still another modified form of the invention; and

Fig. 9 is a fragmentary, transverse sectional view, of the modified form shown in Fig. 8.

For the purpose of illustrating my invention I have shown in the accompanying drawings forms thereof which are at present preferred by me, since the same have been found in practice to give satisfactory and reliable results, although it is to be understood that the various instrumentalities of 65 which my invention consists can be variously arranged and organized and that my invention is not limited to the precise arrangement and organization of the instrumentalities as herein shown and described.

Referring to Figs. 1, 2, and 3, A designates my improved pasteboard cigar box which comprises a lower portion or container 11 and a hinged lid 12. The lid 12 has longitudinal and lateral flanges 13, 14 respectively, the flanges 14 being formed with slots 15 in which the shank of a headed pin or eyelet 16 rides. The smaller ends 17 of the headed pins or eyelets 16 are each secured near one end of an arm or flat strip 18 formed of cel-

luloid, metal, or fabricated material, the other end of which is pivoted on an eyelet or the like 19, fastened in the upper edge of the side wall of the container 11. In the present instance the side wall of the container 85 is disclosed as a composite structure comprising the main body portion 21 against the inner face of which is secured a band or tray 20 the upper edge of which projects above the upper edge of the body portion 21, thus pro-

ducing what is known as a ledge box or container. The flanges 13, 14 of the lid, when the lid is in closed position, confront the projecting portions of the tray 20 and seat at their lower ends upon the upper edge of 90

the body portion. When the lid is in closed position, the connection 18 lies between the projecting portion of the tray and the flange 14 of the lid. It will be noted that in this position it cannot interfere with or strike 100

against any of the contents of the container to damage the same. During closing or opening of the lid the headed pin 16 will ride in the slot 15 and by its engagement against 5 one end of this slot will serve to limit opening of the container lid. After the lid 12 is raised, as shown in Fig. 1, the said lid 12 will be maintained in the erect or somewhat 10 sloping position shown by the frictional engagement of the pins 16 with the edges of the material abounding the slots 15, thereby displaying the label 23 used to advertise or indicate the particular brand of cigars in the instant container. In addition, when my 15 pasteboard box is removed from a show case in order to permit a customer to select one or more cigars, the lid 12 alone will be grasped by one hand of the dispensor without requiring the container 11 to be supported by the other hand. This procedure is, of 20 course, impossible to perform with a conventional wooden cigar box, the lid of which when open will fall into a flat position or parallel with the bottom of the attached container, thereby preventing in large measure the label on the inside of the container from being seen while the container itself while being lifted must be sustained generally with the other hand. The lid of the 25 conventional wooden cigar box will of course assume its flat position unless the hand is continually employed to support same. The above disadvantages for the conventional cigar boxes are completely obviated 30 by my pasteboard cigar box, as pointed out above, which may be manufactured and sold more economically than wooden boxes and which further lends itself to the most variegated and artistic effects not possible to 35 wooden boxes.

In Figs. 4, 5, I have illustrated a slight variation of the form shown in Figs. 1, 2, and 3, which consists in providing the slots 15 with an offset 24 wherein the pins 16 are adapted 40 to seat, as shown in Fig. 4. The slots 15 with the offset portions 24 are of the bayonet type and may be preferred by some. The other details of this form of my invention are the same as those shown in Figs. 1, 2, and 3, this 45 being indicated by a corresponding similarity in the reference numerals shown.

In Figs. 6, 7 the inset ledge 25, fastened on the inside of the container 26, has secured thereto a pin or eyelet 27 in which is rockingly mounted a strip 28 of celluloid or other suitable material, to which is pivotally secured a second strip 29 of similar material, hinged to a lid 30 by a pin or eyelet 31 fastened in the said lid 30. The second strip 29 is formed with a small lip or bent-over edge 32 which serves as a stop to maintain both strips 28, 29 in locked operative position for maintaining the lid 30 in the desired erect or sloping position with a view to the 55 advantages pointed out for the forms shown

in Figs. 1 to 5 inclusive. While the principal form of the invention, as shown in Figs. 1, 2, and 3, offers certain advantages in that it provides for a more sure retention of the lid in the desired erect or sloping position, 70 the form shown in Figs. 6 and 7 presents an alternative, if desired.

In Figs. 8 and 9 still another modification is shown wherein the lid 33 is provided with a longitudinal slit 34 which receives the thin, 75 flat strip or arm 35 which is hingedly connected as at 36 in any suitable manner to the inset ledge or shoulder 37 of the container 38. The arm 35 has a notch 39 which forms a hook 40 to engage the lower margin of the material adjacent the slit 33, thereby locking or maintaining the lid 33 in the position shown in Fig. 8.

The general purpose and advantages of the boxes forming the present invention have 80 been in large part indicated above, it being noted that up to the present time pasteboard boxes as cigar containers were considered impractical, one of the chief objections being in view of the mechanical disadvantages attendant upon the conventional lid employed 85 and the means used for supporting same.

I am aware of the Isaacson et al. Patent No. 1,056,996, for a lid supporter for boxes, but the device disclosed therein not only requires manipulation of the supporting arm 90 6 but it has also the disadvantage that the said supporting arm protrudes downwardly into the box among the cigars therein, thereby frequently breaking or spoiling some of 95 the cigars and frequently preventing the closing of the lid itself. In my device the lid supporting arm accomplishes its functions automatically, so to speak, while the lid is being raised or lowered, without coming 100 into contact with the cigars.

I am aware that the invention may be embodied in other specific forms without departing from the spirit or essential attributes thereof, and I therefore desire the present 110 embodiment to be considered in all respects as illustrative and not restrictive, reference being had to the appended claims rather than to the foregoing description to indicate the scope of the invention.

Having thus described my invention what I claim as new and desire to secure by Letters Patent, is:—

1. The combination with a cardboard container of a hinged lid therefor having a flange which, in the closed position of the lid, opposes the upper end of the side wall of the container, a connection between the side wall of the container and said lid including a rigid element, said rigid element being pivoted at one end to the outer face of the side wall of the container and at its opposite end having means slidably engaging in a slot in the flange of the lid, said rigid element in the closed position of the 120

lid being disposed between said flange and the side wall of the container.

2. A cardboard container having an up-standing side wall formed adjacent its upper end with an inset ledge, a lid hingedly connected to said container and having a flange adapted to oppose the upper end of said container side wall and seat upon said ledge, a lid-supporting flat strip pivotally connected to the container wall above said ledge at one end, and means on said flat strip slidably engaging in a slot formed in said flange of the lid whereby said flat strip will be disposed between the side wall and the flange above said ledge when the lid is in closed position.

JOSEPH D. MYERS.
